(57) **CLAIM**

The ornamental design for an electronic atomizing device, as shown and described.

DESCRIPTION

FIG. 1 is a front, right, top, perspective view of an electronic atomizing device showing my new design;

FIG. 2 is a rear, left, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a perspective view with the electronic atomizing device shown in state of use.

The broken lines are for the purpose of the depicting portions of the electronic atomizing device and form no part of the claimed design.

1 Claim, 9 Drawing Sheets
